(57) **CLAIM**

The ornamental design for a pull up exerciser, as shown and described.

DESCRIPTION

FIG. 1 is a front, right side, top perspective view of a pull up exerciser, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is an enlarged view of detail "9" identified in FIG. 1; and,

FIG. 10 is an enlarged view of detail "10" identified in FIG. 1.

The dashed broken lines in the figures illustrate portions of the pull up exerciser that form no part of the claimed design. The dash-dot-dash broken lines in FIGS. 1, 9 and 10 depict the bounds of the enlarged views and form no part of the claimed design. The broken line rectangular boxes with an "x" show stitching and form no part of the claimed design.
